(57) **CLAIM**

The ornamental design for a front panel for an audio console, as shown and described.

DESCRIPTION

FIG. 1 is a front elevation of the front panel for an audio console of Applicants' invention; and,

FIG. 2 is a front lower perspective view showing the front panel for an audio console of Applicants' invention.

The broken line showing on FIGS. 1-2 is for illustrative purposes only and forms no part of the claimed design.
